UNITED STATES PATENT OFFICE.

LEVIN H. CLOGG, OF PHILADELPHIA, PENNSYLVANIA.

DESIGN FOR A TIP-CUP FOR UMBRELLAS.

SPECIFICATION forming part of Design No. 20,290, dated November 11, 1890.

Application filed June 27, 1890. Serial No. 357,004. Term of patent 3½ years.

To all whom it may concern:

Be it known that I, LEVIN H. CLOGG, a citizen of the United States, residing at Philadelphia, in the State of Pennsylvania, have invented a new and original Design for Umbrella and Parasol Tip-Cups, of which the following is a specification, reference being had to the photograph annexed to and forming part of this specification.

My invented design is clearly shown in the drawing forming part of the specification, wherein the leading or characteristic features comprise a cylindrical tip-cup for umbrellas or parasols, having a series of knobs or projections B arranged in quincunx order upon its external peripheral surface.

I claim—

The design for umbrella or parasol tip-cups, substantially as shown and described.

In token whereof I have hereto set my name this 25th day of June, 1890.

LEVIN H. CLOGG.
